Application April 18, 1940, Serial No. 330,348

1 Claim. (Cl. 235—61.5)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to a deflection or lead transmitter, and while intended for general use, it is particularly adapted for use in the fire control system of our U. S. copending application, Serial No. 312,380, filed January 4, 1940.

It is an object of the invention to provide a deflection transmitter which may be used to directly transmit a principal computed deflection or modify such principal deflection in accordance with factors affecting the deflection pointing correction.

It is a still further object of the invention to provide a deflection transmitter which may be used to displace the corresponding deflection or lead index of a central control box in the manner the deflection transmitters 14 and 15 are used in the above referred to copending application, or to directly impress the output deflection upon the sight of a gun.

The specific nature of the invention as well as other objects and advantages thereof will clearly appear from a description of a preferred embodiment as shown in the accompanying drawings in which:

Fig. 1 is a perspective view of a deflection transmitter conforming to our present invention;

Fig. 2 is a horizontal section through the transmitter taken just below the transmitter dial;

Fig. 3 is an axially vertical section of the transmitter.

Referring now to the drawings by characters of reference there is shown a deflection or lead transmitter generally indicated at 10 suitable for use in transmitting either vertical or lateral leads or deflections from a lead computer to a gun or central control box, such for example, that it may be employed to carry out the functions of the transmitters 14 or 15 disclosed by the schematic fire control system in Fig. 1 of our copending application above referred to.

The transmitter 10 comprises a casing 11 formed in any convenient manner to provide a centrally disposed generally cup shaped portion 12 an annular flange 13 extending outwardly from the upper edge portion of the cupped part 12 in a plane substantially normal to the axis of the cupped portion. The bottom of the cupped portion 12 is suitably formed with an axially arranged depending downwardly opening socket forming element 14 adapted to house any desired means, herein shown as an interiorly threaded

sleeve 15 secured within the socket, for detachably receiving a supporting post or standard 16. As is well understood in the art the socket forming element 14 may be reinforced by the circumferentially spaced reinforcing webs 17 extended between the bottom of the cupped portion 12 and element 14 shown in Fig. 3.

The interior of the cupped portion 12 is provided with inwardly extending circumferentially spaced abutments 18 which receive the flange 19 of a tubular bearing bracket 20 disposed within the cupped portion in coaxial relation. The abutments 18 support the flange 19 at any desired height above the bottom of the cupped portion 15 and are bored and interiorly threaded, or otherwise suitably formed, to receive removable fasteners 21 for removably securing the bearing bracket to the abutments. As shown more particularly in Fig. 3 the plane containing the upper 20 surface of the bearing bracket 20 terminates slightly below the plane containing the uppermost surface of flange 13 and the bracket is formed to receive spaced upper and lower bearings 22 and 23, respectively, in which a shaft 24 is journaled axially of the bearing bracket and cupped portion 12. Shaft 24 projects above the plane containing the upper surface of the upper bearing a slight distance and is retained in such position by a shoulder 25 on the shaft which 30 engages the upper bearing 22. A worm wheel 26 is secured to the lower end portion of shaft 24 in abutting relation with the lower bearing 23 and serves to maintain the latter in its assembled relation in the bearing bracket 20.

On the outside of the tubular bearing bracket 20 a second worm wheel 26' is mounted concentric thereto by means of the spaced upper and lower bearings 27 and 28 suitably secured in position by an adjustable nut 29 having a seal retaining groove 30 in its upper surface and adapted to be locked in adjusted position by a set screw 31. Preferably the upper surface of the worm wheel 26' terminates in a plane slightly below the plane of the upper surface of flange 13 and slightly 40 above the plane containing the upper surface of bearing bracket 20.

Interiorly of its peripheral portion 32 the flange 13 is recessed to provide an annular seal retaining groove 33 and recessed portion 34 adapted to receive a circular dial 35 positioned with its upper surface in planar relation with the upper surface of the peripheral portion 32 of the flange.

The dial 35 is centrally apertured at 36 to snugly receive the shoulder 25 on shaft 24 and 55 is secured to the worm wheel 26' in planar rela-

tion with the peripheral portion 32 of flange 13 and concentric with shaft 24 by removable fasteners 37 and with suitable seals 38 disposed in the grooves 30 and 33 engaging the lower surface of the dial in sealed relation.

A time of flight and target speed arm 39 having parallel edges is secured to the shoulder 25 of shaft 24, as by removable fasteners 40, with its edges laterally offset from and parallel to a radius of the dial as more particularly shown in Fig. 1. The arm 39 is suitably graduated in target speeds, such as yards per second, on one of the parallel fiducial edges, and graduated in units of time of flight, such as seconds, on the other fiducial edge. These two scales may be used interchangeable since target speed is proportional to time of flight. A scale pointer 41 is secured to the outer end of arm 39 and terminates on a radial line through the axis of the chart parallel to the edges of the arm 39. Scale pointer 41 is read against a scale on the peripheral portion 32 of flange 13 hereinafter described. To facilitate reading the target speed or time of flight scales on the arm 39 against the curves inscribed on the subjacent dial 35 a rider 42 having inscribed thereon an index 43 is slidably mounted on the arm. The index 43 is adapted to be placed in registration with a desired scale reading on the arm. A pointer 44 also inscribed on rider 42 in alignment with the index 43 terminates on a radial line parallel to the edges of the arm 39.

As disclosed in Fig. 2 a tangential bearing housing 45 made integral with the cupped portion 12 of casing 11 or otherwise affixed thereto extends outwardly any convenient distance from the lower portion of the cupped part 12. A bearing sleeve 46 is secured within the bearing housing 45 as by the set screw 47 and carries in any desirable manner spaced bearings 48 in which a shaft 49 is journaled in alignment with the worm wheel 26. The inner end of the shaft has a worm 50 secured thereon in meshing relation with the worm wheel 26 and the outer end has secured thereto a handwheel 51. The housing 45 is provided with an angle outlet 52 intermediate its ends in which the coupling shaft 53, adapted to be coupled with a flexible transmission cable 54, is journaled in geared relation with the shaft 49 through the intermeshing gears 55, 56 secured to the shafts, respectively.

A second tangential housing indicated at 57 in Fig. 2 suitably spaced circumferentially from the housing 45 is made integral with or otherwise affixed to the cupped portion 12 of casing 11 and opens into the cupped portion in proximity to the teeth of worm wheel 26'. Spaced bearings 58 mounted within the housing 57 and a drive shaft 59 is journaled in the innermost bearing 58 having a worm 60 secured thereto disposed in meshing relation with the worm wheel 26'. A flexible cable coupling shaft 61, adapted to be coupled with the flexible cable 62 operable by the super-elevation transmitter 63, is journaled in the outer bearing 58 and interconnected with shaft 59 by the sleeve 64 and pin connections 65 indicated in Fig. 2.

Symmetrically arranged circumferentially relative to the housings 45 and 57 is a radial extending handle bracket 66 integral with or otherwise secured to the cupped portion 12 and bearing a socket within its outer end portion adapted to receive suitable means, such as the interiorly

threaded bushing 67 secured by means 68, unto which a handle may be removably secured.

The housings 45, 57 and bracket 66 extend outwardly substantially the same radial extent as flange 13 whereby when the handle 70 is detached from the transmitter the latter may be packed in a chest of a width corresponding closely with the diameter of the flange 13.

To provide a convenient place to dispose of the super-elevation transmitter 63 when the same is not in use a hook 71 is secured to the post 16 upon which the transmitter 63 may be detachably secured.

The peripheral portion 32 of the flange 13 has a scale 72 engraved or otherwise inscribed thereupon of angular units of deflection or lead, for example in mils, and when the transmitter is employed in the fire control system disclosed in Fig. 1 of our copending application above referred to this scale will be coordinated with the scale 51 or 51' of the lead transmitter scales on the control box 11 shown therein. The deflection curves on the dial 35 are plotted by polar coordinates and agree in numbering with the scale 72 in the same order.

The polar curves on dial 35 are mutually perpendicular to a radial line passing through the center of rotation of the dial 35 and this line designated as 300 is covered up in Fig. 1 by arm 39. The curves on the dial are plotted by using vectorial angles proportional to the lead for a given target speed and the polar radii proportional to the target speed. The dial 35 is zeroized by bringing line 300 thereon in alignment with line 300 on the stationary scale 72. In an illustrated example if it is assumed that a normal distance from the center of rotation of dial 35 corresponds to 50 yards per second target speed, it will be seen that when the rider 42 is set with its index 43 on the target speed graduation on arm 39 of 50 yards per second and the associated pointer 44 on rider 42 placed in coincidence with a given deflection curve on the dial 35 that pointer 41 on arm 39 will indicate a lead on scale 72 numerically the same as the deflection curve. For speeds other than the normal speed of target of 50 yards per second the rider 42 will be so set and in following a given deflection curve on the dial 35 with the rider so set the pointer 41 will indicate a lead on scale 72 corresponding to the ratio of the actual or target speed set on the arm 39 to the normal target speed multiplied by the lead for a target traveling at normal target speed. The target speed and range being correlated by the lead computer does not enter into the operation of the transmitter per se. In lieu of using target speeds the time of flight may be used and the scale in seconds on arm 39 is such a scale to be used in lieu of the target speed scale. This is so since target speed is proportional to time of flight.

In operation the transmitter will be set up by inserting the post 16 in bushing 15 and handle 70 in bushing 67. The post will then be placed into the earth or other suitable supporting medium and cables 54 and 62 coupled with their respective coupling members 53 and 61, respectively. The dial 35 will be zeroized by bringing its normal 300 which is hid by arm 39 in Fig. 1 and which extends normal to all curves on dial 35 and which comprises a straight line passing through the center of rotation of dial 35 into coincidence with the normal of 300 on scale 72. The operator on arm 39 will receive the target speed from any source for determining such data, for example

61.5

2,335,890

3

the lead computer, and set the index 42 on arm 39 accordingly. The operator on handwheel 51 will then cause the pointer 44 to follow the proper deflection curve on dial 35, the deflection curve to be followed being designated by the lead computer. In following the curves on dial 35 with pointer 44 the shaft 49 and gearing 56-55 will drive coupling 53 and flexible cable 54 to either displace the sight of a gun or scale of another transmitter, where the transmitter is used in the same capacity as the transmitter 14 or 15 of Fig. 1 of the above referred to copending application cable 54 will correspond to either one of cables 17.

Where the lead transmitter of this invention is employed to transmit vertical leads the superelevation pointing correction may be added to the principal vertical deflection through displacement of the dial 35 from its oriented position with its normal 300 in coincidence with the normal 300 of scale 72 by means of the superelevation transmitter 63, flexible cable 62, coupling 61, shaft 59 and worm 60 which meshes with worm wheel 26' carrying the dial. It will be observed that by this arrangement that the output lead of the transmitter will be increased or decreased an amount proportional to the superelevation.

In those cases where the transmitter is to be used exclusively for the transmission of lateral leads the worm 26', housing 57 and associated shafting and gearing may be dispensed with entirely in which case the dial 35 will be suitably secured to the flange 13.

In all cases the ratio of the gearing employed will be coordinated with the scales, output shafts,

and complementary instruments of the fire control system in which the transmitter is used so that the output leads will cause proportional movements of the elements upon which they are impressed.

Having now particularly described what is at present regarded as a preferred embodiment of our invention what we claim is:

In a lead determining and transmitting device 10 of the type which employs a polar chart, means for turning the said chart, and an angularly adjusted arm provided with a rider radially adjusted in accordance with the speed of the target, the combination of a casing, an annular flange 15 circling the said casing and serving to support the outer portions of the chart centered on the top surface of the said casing and flange, a handwheel disposed at one side of the said casing and operatively connected to the said arm to angularly adjust the arm, a stud shaft journaled in 20 the said casing and operatively connected to the said handwheel and provided with means outside the said device adapted to be connected to a gun, whereby manipulation of the said handwheel in 25 adjusting the said arm to the determined lead is adapted to regulate the said gun in accordance therewith, and a superelevation transmitter in the form of a separate, smaller unitary casing operatively connected to the said chart turning means 30 to turn the same through a flexible shaft.
